Primary Examiner — Catherine Ho

(57) **CLAIM**

The ornamental design for electronic shelf label having a lamp hole surface shell as shown and described.

DESCRIPTION

1. Electronic shelf label having a lamp hole surface shell
  2. Electronic shelf label having a lamp hole surface shell
- 1.1 :Front Perspective
1.2 :Front view of 1.1
1.3 :Back view of 1.1
1.4 :Left view of 1.1
1.5 :Right view of 1.1
1.6 :Top view of 1.1
1.7 :Bottom view of 1.1
1.8 :Enlarged detailed view of portion 1.8 of 1.1
1.9 :Enlarged detailed view of portion 1.9 of 1.2
1.10 :Cross-sectional view taken along line 1.10-1.10 in 1.2
1.11 :Enlarged detailed view of portion 1.11 of 1.10
1.12 :Enlarged back perspective view of the lamp hole surface shell portion, isolated for clarity of illustration
2.1 :Front Perspective
2.2 :Front view of 2.1

(Continued)

2.3 :Back view of 2.1
2.4 :Left view of 2.1
2.5 :Right view of 2.1
2.6 :Top view of 2.1
2.7 :Bottom view of 2.1
2.8 :Enlarged detailed view of portion 2.8 of 2.1
2.9 :Enlarged detailed view of portion 2.9 of 2.2
2.10 :Cross-sectional view taken along line 2.10-2.10 in 2.2
2.11 :Enlarged detailed view of portion 2.11 of 2.10
2.12 :Enlarged back perspective view of the lamp hole surface shell portion, isolated for clarity of illustration
The broken line showing of the electronic shelf label having a lamp hole surface shell is for the purpose of illustrating portions of the article and forms no part of the claimed design.
